(57) **CLAIM**

The ornamental design for a drill bit as shown and described.

DESCRIPTION

FIG. 1 is a bottom, front perspective view of a drill bit showing a first embodiment of our new design;

FIG. 2 is a bottom, rear perspective view of the drill bit of FIG. 1;

FIG. 3 is a front elevational view of the drill bit of FIG. 1; FIG. 4 is a rear elevational view of the drill bit of FIG. 1; FIG. 5 is a left side elevational view of the drill bit of FIG. 1;

FIG. 6 is a right side elevational view of the drill bit of FIG. 1;

FIG. 7 is a bottom plan view of the drill bit of FIG. 1;

FIG. 8 is a bottom, front perspective view of a drill bit showing a second embodiment of our new design;

FIG. 9 is a bottom, rear perspective view of the drill bit of FIG. 8;

FIG. 10 is a front elevational view of the drill bit of FIG. 8;

FIG. 11 is a rear elevational view of the drill bit of FIG. 8; FIG. 12 is a left side elevational view of the drill bit of FIG. 8;

FIG. 13 is a right side elevational view of the drill bit of FIG. 8; and,

FIG. 14 is a bottom plan view of the drill bit of FIG. 8. The broken lines (short dash—short dash—short dash) in FIGS. 1-14 form no part of the claimed design.

1 Claim, 14 Drawing Sheets
